(57) **CLAIM**

The ornamental design for an accessory mounting track as shown and described.

DESCRIPTION

FIG. 1 is a front perspective view of an accessory mounting track.

FIG. 2 is a front elevational view of the accessory mounting track shown in FIG. 1, the back, top and bottom views being mirror images thereof; and,

FIG. 3 is a left side elevational view of the accessory mounting track shown in FIG. 1, the right side being a mirror image thereof.

The area within the broken lines on the left side of the accessory mounting track in FIGS. 1 and 3 forms no part of the claimed design.

The area between the broken lines along a longitudinal center of the accessory mounting track in FIGS. 1 and 2 forms no part of the claimed design so as to reflect that the accessory mounting track is an indeterminant length.

1 Claim, 3 Drawing Sheets
